COSMETIC CONTAINER

William E. Sydlowski, Seymour, Conn., assignor to The Risdon Manufacturing Company, Naugatuck, Conn., a corporation of Connecticut

Filed Jan. 19, 1962, Ser. No. 68,374

Term of patent 14 years

(Cl. D86—10)

FIG. 1 is a front elevation of a cosmetic container embodying the inventive design;

FIG. 2 is a top view of the container;

FIG. 3 is a side elevation of the container;

FIG. 4 is a side elevation showing the cosmetic holder being pivoted to an operative position;

FIG. 5 is a front elevation showing the container with the cosmetic advanced; and

FIG. 6 is a side elevation showing the container with the cosmetic advanced.

The broken line showing of the cosmetic in FIGS. 4, 5 and 6 is for illustrative purposes only.

The design has for a dominant feature an enlarged elliptical base from which a pair of tapered laterally ex-

tending arms project upwardly to substantially the upper end of a cosmetic casing when the latter is fully contracted within the arms, all as shown.

I claim:

The ornamental design for a cosmetic container, substantially as shown and described.
